CASEMENT WINDOW

Filed June 4, 1928

UNITED STATES PATENT OFFICE

KARL F. JORSS, OF WASHINGTON, DISTRICT OF COLUMBIA, ASSIGNOR, BY MESNE ASSIGNMENTS, TO CRITTALL CASEMENT WINDOW COMPANY, OF DETROIT, MICHIGAN, A CORPORATION OF MICHIGAN

CASEMENT WINDOW

Application filed June 4, 1928. Serial No. 282,602.

This invention relates to improvement in metallic window sashes and frames, and more specifically to metallic frame and sash structures in which the sash is pivotally mounted within or to the frame.

5 The primary object of the invention is the provision of an installation, such as above referred to, which effectually seals the assembly against the entrance of rain, air and dust, 10 when the sash is in its closed position, yet offers no frictional resistance against movement of the latter to open position. In the attainment of this result, I provide for two parallel lines of metal to metal contact when 15 the sash is closed, whereby to prevent entrance of rain between the sash and frame, in combination with elongated weather strips of felt or the like, so mounted as to exclude air and dust when the sash is in its closed position.

20 Another object of the invention is the provision of means so housing the felt weather strip as to permit the latter to spread laterally, on each of its sides, as will be herein- 25 after more particularly referred to.

Other objects of the invention will be made apparent in the following specifications when read in connection with the accompanying drawings forming a part thereof.

30 In said drawings:

Fig. 1 is a perspective view showing a window sash adapted to be pivotally secured to a supporting frame.

Fig. 2 is a fragmentary perspective view, 35 partly in section, showing the casing and sash, with the latter in closed position, and,

Fig. 3 is a sectional view, taken laterally through the sash and frame, and showing the sash in closed position.

40 While I have chosen to illustrate the invention applied to a sash which is mounted on pivots arranged in vertical alignment, it is within the scope of the invention to connect the sash and frame by pivots positioned in

45 lateral alignment, one in each side of the sash and frame, or the pivotal points may be at the top or bottom of the structure, as will be understood.

Now referring specifically to the drawings, 50 in which like reference numerals indicate like

parts throughout the several views, 1 indicates the rail of the sash member, here shown as provided with hinges 2, in vertical alignment, and adapted to pivotally secure the rail to the frame rail 3.

55 The sash rail 1 and frame rail 3 are built up from extruded metal forms, the sash having the usual glass 4 secured thereto, in the customary manner, the rail being provided with integral, vertically extending flanges 5, at 60 its top and bottom, and with similar but laterally extending flanges 6 on each side. The frame rail 3 is equipped at the front, and on each side with a vertically-extending integral flange 7, adapted for abutment by the flange 6 on the sash rail, and with a flange 8 on each side, and extending inwardly from the side rails.

65 It will be understood that the sash rail 1 extends entirely around and defines the shape 70 and size of the sash, and the same is true of the rail 3, with respect to the frame. As clearly illustrated in Figs. 2 and 3, the inner edge of the rail 1 is provided with an integral, offset portion 9, and extending entirely 75 around the rail, said inner edge also carrying a flanged extension 10, terminating short of the flange 8 on the frame. The extension 10 is spaced from the offset 9, to provide an elongated housing for a felt weatherstrip 11, and,

80 as clearly illustrated in Fig. 3, the offset 9 is provided with a shoulder 12, spaced from the flange 8, and with a lip 13 normally in contact with said flange 8, but so positioned as to permit limited expansion of the projecting outer edge of said strip. Such assembly mani-

85 festly provides space on each side for lateral expansion of portions of the weatherstrip 11 extending beyond the main housing, when the sash is closed and tightly secured in position by the usual cam or latch members, not herein illustrated. The strips 14, which receive the glass 4, are secured to the rail 1 and to the rear face of the offset 9.

90 In view of the foregoing it is obvious that 95 I have provided a structure which, as nearly as possible, is adapted to operate with 100% efficiency in the exclusion of air, dust and moisture. When the sash is closed the metal to metal contacts 15 and 16, Fig. 3, excludes 100

the rain or snow, the contact with the flange 8 of the flattened and laterally spread weather strip 11, effectually preventing the entrance of air, and of dust when the weather is dry.

5 The provision of space to permit lateral expansion of that portion of the strip 11 which is not confined in the elongated housing is of great importance. Such strips are naturally 10 resilient, and in assembly the greater portion thereof is tightly impacted within the housing formed between the offset 9 and the extension 10, the outer edge of the strip projecting for contact with the flange 8. It is clear 15 that the amount of dust and air excluded is in direct proportion to the surface contact of the strip with the flange 8. By providing the elongated recess or pocket for the projecting edge of the strip 11, the latter is permitted 20 to expand on each side when compressed by the closing of the sash, and spreads along the face of the flange 8, the natural resilience of the strip causing portions thereof to spring into and fill any depressions or irregularities 25 which may be in the contacted surface of the flange 8, and most effectually prevent the passage of air or dust.

Modifications of the structure herein disclosed may be suggested to those skilled in the art, but my invention covers all embodiments falling fairly within the scope of the appended claims.

I claim:

1. The combination with a metallic 35 window frame provided with two laterally extending flanges located in separated planes, of a metallic sash pivoted to said frame and provided with members adapted for contact with said flanges when the sash is closed, an 40 offset portion integral with one of said members, and provided with a longitudinally extending groove, an expansible weatherstrip positioned in said groove and having its edge projecting therefrom, one side of said edge 45 being free for unlimited expansion, and means carried by said offset portion and positioned to limit lateral expansion of the other side of said edge when compressed by contact with a flange on said frame when the sash is 50 closed.

2. A window structure comprising a metallic frame member and a metallic sash member pivotally connected thereto, means carried by said members adapted, when the sash 55 is closed, to provide a line of metal-to-metal contact therebetween, an elongated groove extending around one of said members, and formed of two spaced parallel flanges of unequal length, a compressible weatherstrip mounted in said groove and having an edge 60 extending therefrom, the longer flange of the groove-containing member being positioned for contact by said edge, and the shorter 65 flange of said groove permitting lateral ex-

pansion of said edge thereover when the sash is closed.

In testimony whereof I affix my signature.

KARL F. JORSS.
